UNITED STATES PATENT OFFICE.

JOHN W. LEEK, OF CINCINNATI, OHIO.

CARRIAGE-TOP.

SPECIFICATION forming part of Letters Patent No. 375,553, dated December 27, 1887.

Application filed August 29, 1887. Serial No. 248,195. (No model.)

To all whom it may concern:

Be it known that I, JOHN W. LEEK, a resident of Cincinnati, in the county of Hamilton and State of Ohio, have invented certain new 5 and useful Improvements in Carriage-Tops, of which the following is a specification.

The object of my invention is to provide a neat finish for the edge of canopy-tops of phaeton, surrey, or like conveyances, and to 10 provide a novel metallic water-drip, preventing water from coming in contact with the head-lining and rotting it out, all of which will be hereinafter described and claimed, reference being made to the accompanying 15 drawings, making a part of this specification, in which—

Figure 1 is a perspective view of the improved top. Fig. 2 is a top plan view of the frame-work, showing its construction. Fig. 20 3 is a cross section through the frame and molding.

A represents the frame of the top; a, bows to support the cover B.

C represents the ordinary top-supporting 25 irons.

D represents the head-lining; E, a filling-piece of any suitable material; F, metallic molding of any design.

G represents a curtain, hung by hook H to 30 staple h, driven in the frame A.

The construction is as follows: The head-lining D is stretched on the under side of frame A and tacked to the outer edge of same. Then the filling-piece E is securely fastened 35 over it. The cover B is then stretched over the top and tacked to the filling-piece E. The metallic and finishing molding F is then put on and clamped down by suitable tools upon the filling-piece E, as shown in Fig. 3.

The great objection in having the bottom 40 of the molding on a plane with the head-lining is, that it allows the water shed by the top to follow the molding around and wet the head-lining. I prevent this by having the metallic molding project below the head-lining, forming a drip for the water. It also 45 forms a shed or protection for the top part of

the curtain and its fastening devices, which is secured to the under side of the frame A, thereby making a neater top, and one which 50 will shed the water much better than other constructions hitherto used, because the curtain joint is protected and hidden from view.

Having described my invention, what I claim is—

1. A canopy-top for vehicles, consisting of the top frame, A, the head-lining D, secured at its edges to said frame, the filling-piece E, secured to the side of the frame over the head-lining, the covering B, extending over the 6c frame and attached to the filling-piece, and the outer metallic molding, F, having its upper and lower edges secured upon the filling-piece and protecting the attached edges of the covering, substantially as described. 65

2. A canopy-top for vehicles, consisting of the top frame, A, the head-lining D, secured at its edges to the frame, the filling-piece E, attached to the top frame and projecting downward below the under side of the head-lining, 70 the covering B, extending over the frame and secured to the front of the filling-piece, and the molding F, having its upper and lower edges extending around and clamped upon the edges of the filling-piece, substantially as de- 75 scribed.

3. The combination, with the open frame A, having the transverse bows a, the covering B, stretched over the bows, the lining D, secured to the frame, the filling-piece E, attached to so the frame and around which the covering extends, said filling-piece extending below the plane of the lining to form a water-drip, and the molding F, having its upper and lower edges crimped around the edges of the filling-piece and holding the covering in place, substantially as described. 85

In testimony whereof I have hereunto set my hand.

JOHN W. LEEK.
